BADGE HOLDER OR THE LIKE

Gabriel G. Tauber, Victor Building, 724 9th St. NW.,
Washington, D.C.

Filed Mar. 24, 1965, Ser. No. 84,420

Term of patent 14 years

(Cl. D29—2)

The cord holding means has been omitted from FIGURES 1 through 4 for convenience of illustration and the cords are shown in FIGURES 6 and 7 broken away also for convenience of illustration.

I claim:

The ornamental design for a badge holder or the like, as shown and described.
